[57] CLAIM

The ornamental design for squirrel guard, as shown and described.

DESCRIPTION

FIG. 1 is a perspective view of a squirrel guard showing my new design;

FIG. 2 is a front elevational view thereof, the rear and side elevational views are identical to the front view shown;

FIG. 3 is a top plan view thereof;

FIG. 4 is a perspective view of a second embodiment of FIG. 1;

FIG. 5 is a front elevational view thereof;

FIG. 6 is a rear elevational view thereof;

FIG. 7 is a top plan view thereof;

FIG. 8 is a left side elevational view thereof, the rear and right side are identical to the left side shown;

FIG. 9 is a perspective view of a third embodiment of FIG. 1;

FIG. 10 is a front elevational view thereof, the rear and side elevational views are identical to the front view shown;

FIG. 11 is a top plan view thereof;

FIG. 12 is a perspective view of a fourth embodiment of FIG. 1;

FIG. 13 is a front elevational view thereof, the rear being identical to the front view shown;

FIG. 14 is a left side elevational view thereof, the right side being identical to the left side shown; and,

FIG. 15 is a top plan view thereof.

The broken lines are for purposes of illustration only and form no part of the claimed design.
